PAUL KREUZHAGE, OF STUTTGART, GERMANY, ASSIGNOR TO THE FIRM OF PAUL LECHLER, OF STUTTGART, GERMANY.

SPRAY-NOZZLE.

1,319,527.

Specification of Letters Patent. Patented Oct. 21, 1919.

Application filed July 15, 1913, Serial No. 779,129. Renewed June 21, 1919. Serial No. 305,910.

To all whom it may concern:

Be it known that I, PAUL KREUZHAGE, a subject of the King of Wurttemberg, residing at Stuttgart, Germany, have invented 5 certain new and useful Improvements in Spray-Nozzles, of which the following is a specification.

This invention relates to spray nozzles and has for its primary object to provide an improved construction combination and arrangement of parts in a device of this character, according to which the degree of atomizing, the amount of liquid used and the size of the spray cone can be controlled 10 by regulating the available pressure in a single conical spiral channel which distributes the liquid uniformly over the spray cone. Toward the attainment of this object, a member is employed which serves as a 15 connecting piece to the fluid-conductor, said member being provided with a frusto conical portion having a conical spiral channel, inclosed in a spray-hood made adjustable on it, and which, in its retracted position 20 bears against the cone and has on its inner wall a flat face at right angles to the longitudinal axis of the orifice. Between this face and the cone there remains a hollow 25 space or chamber. The angle of the cone is 30 preferably about 45 degrees, so that in adjusting the hood, the size of this hollow space need be changed but slightly in comparison to the change in amounts of fluid 35 passing through it. By this construction it becomes possible to vary the whirling effect imparted to the liquid in said chamber before it reaches the orifice. The atomizing 40 action of the nozzle may thus be regulated as desired. At the same time, the current 45 as it issues from the conical spiral channel is being contracted by a conical surface which converges toward a point which is distant from the orifice in said spray-hood a less distance than the axial extent of said chamber.

45 I obtain the mentioned objects by the mechanism illustrated in the accompanying drawings in which:

Figure 1 is a sectional view, and

Fig. 2 is a plan view the spray-drum being taken off.

The water under pressure is conducted through the conducting tube 1 into the helical conducting-channel 2 provided in the body 3; this body is substantially formed as 55 a cylindrical pipe 4 the one end of which

terminates in a hexagonal flange 5, the other end of the said pipe being tapered to a truncated cone 6. The cylindrical portion 4 of the body 3 is provided with an inner thread 7 and with an outer thread 8. The 60 conducting-tube 1 is attached to the cylindrical portion 4 by means of the mentioned inner thread, the spray-drum however is coupled to the cylindrical portion 4 by means of the outer thread 8. This spray- 65 drum 9 consists also substantially of a cylinder 10 tapering to a truncated cone 11, this truncated cone being provided with a small orifice 12 at its outer end. The said orifice is an outlet of an interior chamber 13 70 formed also as a truncated cone by the truncated cones 6 and 11. Said interior chamber is made in the form of a truncated cone in order that the spray, in spite of the fact that only one conducting channel 75 is used, may take the form of a symmetrical spray cone, rather than a distorted shape, a cross section of which would be an oblique conical section and this, moreover, with a minimum expenditure of water or other 80 liquid. The truncated cone-shaped portion 6 of the body 3 bears against the inner face of the cone 11 of the spray-drum 9; in consequence the liquid will flow only through the helical conducting-channel 2; in this 85 case the nozzle sprays with the minimum expenditure of water and with the finest spray. If it is desired to regulate the quantity of liquid and the fineness of the mist, it is only necessary to provide a space between 90 the cone and the inner face of the truncated cone 11 by screwing off a little the spray-drum 9; for the liquid will flow not only through the helical conducting-channel 2, but also around about the inner face of the 95 cone 11 and through the interior chamber 13 toward the nozzle-orifice. Since the greater quantity of fluid is caused to flow through the helical conducting-channel 2 and the said channel extends along the whole circumference of the cone 11, the fluid flowing through the space between the truncated cones 6 and 11 toward the orifice of nozzle 100 is swept away by the great mass of fluid flowing through the helical channel. If the 105 helical conducting-channel 2 is clogged by dirt or the like, the spray-drum 9 is screwed off a little, so that the dirt or the like can be flushed off. It is not necessary to stop the flow in cleaning the nozzle.

2 What I claim as my invention is:

1. In a spray nozzle, an exteriorly threaded cylindrical tubular body provided with a forwardly extending frusto-conical portion having a spiral channel or groove in the external wall thereof, and a hood comprising a cylindrical body threaded to said exteriorly threaded tubular body and provided with a hollow frusto-conical surface adjustable toward and away from the corresponding frusto-conical portion of said tubular body, said nozzle being provided with an outlet chamber into which said spiral channel or groove empties and with a discharge orifice in the end wall of said hood.

2. In a spray nozzle, an exteriorly threaded cylindrical tubular body provided with a forwardly extending frusto-conical portion having a spiral channel or groove in the external wall thereof, and a hood

comprising a cylindrical body threaded to said exteriorly threaded tubular body and provided with a hollow frusto-conical surface adjustable toward and away from the corresponding frusto-conical portion of said tubular body, said nozzle being provided with an outlet chamber into which said spiral channel or groove empties and with a discharge orifice in the end wall of said hood, 25 the frusto-conical surfaces of said tubular body and hood when in close contact, converging to a center which is distant from said orifice less than the axial extent of said chamber. 30

35 In testimony whereof I affix my signature in presence of two witnesses.

PAUL KREUZHAGE.
